UNITED STATES PATENT OFFICE.

CHARLES F. PYM, OF DETROIT, MICHIGAN, ASSIGNOR, BY MESNE ASSIGNMENTS, TO UNITED SHOE MACHINERY CORPORATION, OF PATERSON, NEW JERSEY, A CORPORATION OF NEW JERSEY.

MACHINE FOR PLACING LASTING-BINDERS.

1,306,120.

Specification of Letters Patent. Patented June 10, 1919.

Application filed July 2, 1913. Serial No. 776,927.

To all whom it may concern:

Be it known that I, CHARLES F. PYM, a citizen of the United States of America, residing at Detroit, in the county of Wayne 5 and State of Michigan, have invented certain new and useful Improvements in Machines for Placing Lasting-Binders, of which the following is a specification, reference being had therein to the accompanying 10 drawings.

This invention relates to machines for use in the manufacture of boots and shoes and more particularly to machines for performing lasting operations, the construction 15 herein shown as an embodiment of the invention comprising mechanism for placing a binder in position to hold a boot or shoe upper formed around and against the end of a last. This application is a continuation 20 of my co-pending application Ser. No. 772,236, upon which Letters Patent No. 1,126,271 were granted on January 26, 1915, in so far as it covers subject-matter disclosed but not claimed in said co-pending application. 25

It has been the usual practice in lasting welt and turn shoes to work the upper around and over the toe end of the last and then secure it in lasted position by drawing 30 a binder into contact therewith around the toe of the shoe and securing the ends of the binder by tacks or other suitable means, the binder being drawn into firm contact with the upper by pulling upon one or both 35 of its ends. It has been found that a heavy pull is necessary upon the ends of the binder to draw it into firm, even contact with the upper owing to the resistance offered by the upper because of its unevenness and the 40 shape of the end of the last. A binder of considerable strength is therefore required to stand the strain, and such a binder is an obstruction in the subsequent operation of permanently connecting the upper to the 45 sole (the term "sole" being used generically herein to include innersole). Where the lasting operation is carried out by means of wiper plates which are forced over the margin of the sole upon the last to form the 50 margin of the upper down thereon and against the lip, a still greater strain is necessary upon the binder in order to draw it firmly into place between the wiper and the

formed down edge of the upper. If, as has been the common practice, the downward pressure of the wiper plates upon the formed over edge of the upper is relieved, the upper is very liable to slip from the position to which it has been carried by the wiper plates thus allowing wrinkles to form. 55 60

One of the objects of this invention is to provide suitable means for applying a binder by pressure directed against the side of the binder, thus relieving the binder of all strains and permitting the use of a wire 65 of light gage or of other suitable material which will not interfere with the sewing operation. A further object of the invention is to provide means for so applying a binder that it will evenly and firmly engage 70 the upper along the entire length of the portion to be held by it.

Another object of this invention is to provide improved mechanism adapted to act in part through a binding wire to force the 75 marginal portion of an upper into lasted position over the feather and against the lip or shoulder of a turn sole or welt innersole. In the illustrated embodiment of this portion of the invention the means so acting is 80 arranged to operate progressively along the two sides of the toe from the end of the toe rearwardly to lay the upper into finally lasted position and leave a binder holding the upper in that position. In the broadest 85 aspect of this portion of the invention, said means for laying the upper in lasted position is adapted to be used, if desired, independently of any binding operation. It will therefore be understood that this invention 90 relates in part to lasting without restriction to any means or any particular method for binding the upper, and the claims are to be understood as limited only as required by the terms thereof. 95

A further object of the invention is to provide means for forcing a binder into position to hold a lasted upper firmly in place against the lip of a sole when such lasting operation is performed by means of wiper 100 plates which are forced over the edge of the sole upon the last to form the upper against the lip. In this combination the means employed for forcing the binder into place is arranged to operate between the wipers and 105 the shoe bottom to form the edge of the

upper and to hold the upper in the position to which it has been carried by the wiper plates while at the same time forcing a binder into binding position. It is within 5 this invention, however, to employ said means to force a tensioned upper into lasted position without the aid of wiper plates and independently of whether or not said means is employed for placing a binder.

10 This invention is useful not only in making welt and turn shoes and in practising the novel method for making such shoes claimed in my co-pending application upon which United States Letters Patent No. 15 1,126,271 has been granted, but the invention is also adapted for use in the manufacture of McKay shoes, and more particularly in practising the invention set forth in my co-pending method application Ser. No. 20 766,471. As I am advised, I am the first to provide mechanism for applying a toe binder exteriorly of the bottom of a shoe in position to hold an upper under tension in lasted relation to the side faces of a last.

25 As more particularly pointed out in said method application, these portions of my invention under immediate consideration have among their advantages the possibility of dividing a toe lasting operation in two parts, 30 the first of which comprises shaping the upper to the exterior side faces of the toe portion of a last and securing it in such shaped condition, and the second part of which consists in securing the marginal portion 35 of the upper to the sole with or without particularly forming said marginal portion of the upper as a step preparatory to securing it to the sole. These portions of the invention are applicable, for example, 40 to the manufacture of McKay and stitch-down shoes as well as to the manufacture of welt and other classes of shoes.

It is also an object of the invention to provide suitable means for holding a binder in 45 position to be engaged by a means for laying it into binding position and, furthermore, to provide a construction and arrangement of parts by which this invention may be applied to or conveniently incorporated 50 in known types of lasting machines and which construction embodies certain new and useful features hereinafter more fully described.

Still another object of the invention is to 55 provide improved means for shaping an upper to a last along the lateral periphery of the last adjacent to the edge of the shoe bottom, the construction shown comprising rolls which are moved progressively along 60 the shoe from the toe end rearwardly.

To these ends the invention consists in the matters hereinafter set forth and pointed out in the appended claims, reference being had to the accompanying drawings in 65 which,

Figure 1 is a side elevation, partially in section, of a known portion of a lasting machine having mechanism embodying this invention in operative position thereon and of a last on which a welt shoe is being made; 70

Fig. 2 is an inverted plan view of the same with the last removed;

Fig. 3 is a front elevation of Fig. 1 with the last removed;

Fig. 4 is a plan view of a last with an 75 upper in lasted position thereon and illustrating the manner in which rolls are employed to lay a binder in place;

Fig. 5 is a view similar to Fig. 1 showing the operation of placing a modified form of 80 binder, such for example as that forming the subject-matter of my co-pending application Ser. No. 766,472, exteriorly around the toe portion of a shoe in position to hold an upper under tension against the side 85 faces of the last and the edge of the sole in accordance with the method set forth in said application Ser. No. 766,471;

Fig. 6 is an enlarged detail of one of the placing rolls and binder holding devices, 90 illustrating a modified construction;

Fig. 7 is an inverted plan view of Fig. 6;

Fig. 8 is a view similar to that of Fig. 3 showing a modified form of binder holding means; and

Fig. 9 is a view similar to that of Fig. 2 showing the modification illustrated in Fig. 8.

For convenience of illustration, a portion of a lasting machine of the type in which 100 wiper plates are employed to form a shoe upper around and against the end of a last, is shown, to some extent, this machine being completely illustrated in United States Letters Patent No. 1,274,590, granted on August 105 6, 1918, but it will be understood that this invention may be applied to other forms and types of lasting machines and that it may be used in the manufacture of welt, McKay, turn or other kinds of work. The 110 construction and arrangement of the mechanism embodying the invention, as shown, is especially adapted for application to a machine of the type shown, but it will be understood that changes may be made to adapt it 115 for use with other types or constructions without departing from the spirit of my invention and it is therefore to be understood that such changes are contemplated and are within the scope of this invention.

In the drawings, A represents the table of a lasting machine and upon this table is secured a suitable bearing bracket B upon which a rocker C is mounted to turn about the pivot bearing D in a vertical plane. 120 Carried by the rocker C is a head E provided with a slot for carrier plates F which are also slotted in their forward edges to receive the formed wiper plates G which are 125 detachably held in the slot and free to move 130

therein. The wiper plates are pivotally connected at H in the usual manner and the carrier members F are free to turn within the slot in the head E, said members being so turned by any suitable means, not shown, attached to the laterally extending ears I of said members. The head E is arranged to have a forward and back or longitudinal movement within the rocker C and is actuated in any suitable manner, not shown. A suitable jack J is provided to support a last K in position in front of the wiper plates, and against a sole rest, Fig. 1, and this jack may be immovably supported in any suitable manner or may be arranged to have, in connection with the sole rest, a vertical movement in time relation to the movement of the rocker C, the parts being constructed and arranged to coöperate in effecting tensioning of the upper and shaping of the upper to the side faces of the last and to the toe portion of the last with or without also shaping the marginal portion of the upper to the marginal portion of the sole N' and laying it into position to be bound against the lip or rib N on the sole.

To lay a binder wire L against the up-standing edge of the shoe upper M upon the last and hold said edge in overworked position against the lip N of the sole N' on the last, a pair of tools herein shown as rollers or rolls 1 are provided and are supported by posts 2 carried upon the forward ends of arms 3 which are pivotally attached at their opposite ends to a sliding block 4 movable upon a guide rod 5 which is secured at its rear end within a bearing 6 attached to the rocker C and is supported at its forward end by a stud 7 secured to the underside of the head E. Carried by the lower end of the stud 7, are rolls 8 which project laterally from the stud beneath the arms 3 and form rolling supports for said arms. Sleeved upon the rod 5 between the stud 7 and block 4, is a coiled spring 9 which tends to normally hold the block at the rear end of its stroke upon the rod, and to move the block against the action of said spring, the block is provided with a cross bar 10 to the ends of which cables 11 are secured and these cables pass over suitable pulleys 12 on the forward edge of the table A and thence downward to a foot pedal, not shown, or other suitable means for exerting a pull upon the cables.

Each post 2 is formed with an off-set 13 so that, as clearly shown in Fig. 2, when the block 4 is at the rear end of its stroke and the posts are thus adjacent to each other near the end of the last, the rolls which are carried upon suitable upwardly extending pins 14 on the upper ends of the off-sets, will be supported adjacent to each other at the extreme end of a last which is supported in lasting position by the jack. The guid-

ing and supporting means for the arms 3 which carry the rolls, is carried by and rocks with the rocker C and head E so that said rolls are always supported at the same relative height to the wiper plates and the parts are preferably so arranged that the upper end of each roll bears against or moves adjacent to the under surface of the wiper plates. The trunnions or pins 14 upon which the rolls turn, engage axial openings in the rolls and said rolls may be lifted off the pins at any time by simply removing the wiper plates.

The carrier arms 3 being pivotally attached at their rear ends to the block 4 are free to swing toward and from each other at their forward ends at each side of the stud 7 to move the rolls 1 toward and from each other, and these arms are normally held swung toward each other by means of a coiled spring 15 connecting them near their forward ends. When a last is supported in lasting position by the jack and the operator causes a forward movement of the block 4, the rolls 1 will be brought into contact with the last at its extreme end and upon further forward movement they will roll along the sides of the last spreading their carrying arms apart against the action of the spring 15 which tends to hold them in firm contact with the last. For use upon a welt shoe, for example, each of the rolls 1 is preferably formed as shown in Fig. 1 with a flange 16 at its upper end and with a downwardly extended body portion 17 which is rounded and preferably formed to in a measure conform to the shape which it is desired to give the edge of the shoe upper along the angle where it is formed over and down upon the edge of the sole. The flange 16 is preferably made of such a width that it will project over that portion of the upper which is worked over the edge of the sole and force the binder wire L engaged by the edge of the flange, firmly into the angle of the upper along the lip of the sole. The edge of the flange on each roll is preferably formed with a slight groove to receive the binder wire. From the foregoing it will be understood that the rolls are adapted to perform an upper shaping operation in addition to, or it may be independently of, a binder placing operation. The body portions 17 of the rolls serve to shape the upper exteriorly of the last bottom to the side faces of the last and by their pressure to roll it smoothly into lasted position in conformity to the contour of the underlying portion of the last and of the edge of the sole. The flange portions 16 of the rolls shape the marginal portion of the upper over the marginal portion of the sole and lay the upper in lasted position thereon. The mounting for the rolls and its operating mechanism is so constructed and ar-

120
125
130

ranged that the rolls are self adapting to different styles or shapes of lasts as, for example, to pointed or wide toes and to unsymmetrical right and left toes.

- 5 To hold the binder wire L against the under surface of the wiper plates G adjacent to the end of the last and in position to be engaged by the flanges of the rolls 1 when the same are moved forwardly, a
 10 spring finger 18 is pivotally supported and carried by each post 2 with its upper side adjacent to the under face of the wiper plates. To so support and carry each finger 18, each post 2 is provided upon one side of its off-set 13 with a laterally projecting lug
 15 19 which forms a bearing for a vertical shaft 20 adapted to turn freely within the bearing, and upon the upper end of this shaft the finger 18 is secured. The lower
 20 end of the shaft 20 projects through its bearing and is provided with a laterally extending arm 21 adjustably secured to the shaft by means of a set screw 22. This arm is adapted to engage the side of the post 2
 25 and thus limit the turning of the finger 18 toward the last. A coiled spring 23 attached to the end of the arm 21 at one end and to the post 2 at its opposite end normally holds the arm in contact with the post
 30 and permits the yielding outward turning of the fingers 18 away from the sides of the last. By adjusting the arm 21 upon its shaft relative to the finger 18 thereon, the normal position of the finger may be
 35 changed as desired so that said fingers will lie closer to or farther away from the last when said last is supported in position adjacent to the wiper plates.
 If found desirable, a binder in the form
 40 of a flat band 24 (see Fig. 5) may be used and this band laid in place around the end of the last for holding the lasted upper in position thereon, by forcing it against the outer face of the upper adjacent to and
 45 below the horizontal plane of the upper surface of the sole upon the last. In laying such a binder in place, the body 17 of the roll is engaged with the side of the band with the flange of the roll projecting over
 50 the upper edge of the band and over the edge of the shoe sole. The position of the band with relation to the worked over edge of the upper will be determined by the shape of the roll and by the height at which it is
 55 supported by suitable holding fingers 25 (see Fig. 6) hereinafter described. The curve of the body of the roll adjacent to its flange will assist in determining the height of the band upon the roll and by providing
 60 rolls of different shapes to suit the work in hand, the band may be accurately placed irrespective of the provision of any flange upon the roll or of the width of the flange. Obviously a plain roll having no flange

whatever may be used to lay such a band in place.

To hold this flat band in position to be engaged by the rolls and forced into binding contact with the lasted upper, each spring finger 25, shown in Fig. 6, may be 70 adjustably secured to each shaft 20 at the proper distance below the finger 18, and thus the band will be accurately supported between the spring fingers in such a position that upon the forward movement of the 75 rolls their flanges will pass over the upper edge of the band and their body portions will be brought into contact with the side of the band.

In Figs. 8 and 9 a modified arrangement 80 of holder for the wire is shown, suitable spring fingers 26 being pivotally attached by screws 27 to the lower side of the head E and bent so that their free ends will lie against the under side of the wiper plates. 85 A spring 28 on each screw 27 holds the finger yieldingly against the wipers and springs 29 are provided to hold the fingers turned toward the last in contact with stops 30. When the rolls 1 pass along the sides of 90 the last they will turn the fingers out of the way and the wire will be held against the under surface of the plates by the fingers until it is carried therefrom by the rolls.

In the operation of lasting and toe binding as illustrated in Figs. 1 to 4, a binder is first slipped into position beneath the wiper and if a wire binder is used it will be placed between the spring fingers 18 and the lower surface of the wipers where it will be held 100 against said surface intermediate its ends with its end portions projecting laterally at each side of the wiper plates. If a flat band is used it will be inserted between the spring fingers 18 and 25 with one side face adjacent 105 to the body of the rolls to be engaged thereby. A last with a shoe upper thereon in position for lasting is then placed upon the jack and the machine set in motion to perform the lasting operation of forming the 110 upper around and against the end of the last with or without forming it over the margin of the sole thereon according as the toe lasting is to be completed in this machine or is to be carried in this machine only 115 so far as shaping the upper to the exterior surfaces of the last. During the operation the lasting instrumentalities, including the wiper plates herein shown and such other lasting devices as may be employed, shape 120 the upper to the last. After the lasting has been carried to the desired point the operator will actuate the block 4 by means of a foot treadle or other device and move the rolls forwardly. If a binder is in place and 125 the work is that shown in Fig. 1, this movement will bring the rolls into contact with the binder and force the same laterally

against the upper at the extreme end of the last. Further forward movement of the rolls will force their flanges in between the lower surface of the wiper plates and the 5 upper surface of the formed over edge of the upper, and the wire will be carried thereby into firm engagement with the upstanding edge of the upper to hold it securely against the lip. After the entrance 10 of the flanges of the rolls between the plates and overworked edge of the upper, further forward movement will carry them along each side of the end portion of the last, and thus the wire will be laid closely into the 15 angle at the base of the lip throughout the end portion of the upper to be held by it, by the rolling contact of the rolls with the wire which will thus be laid progressively into position from the extreme end of the last 20 along the side portions of said end. After the wire has been laid in place its ends may be secured in any suitable manner as by driving tacks into the sole and twisting the ends of the wire around the tacks while the 25 rolls are still in engagement with the wire and holding it firmly in place.

When a flat binder is used to hold the upper in partially lasted position upon the end of the last, the first forward movement 30 of the rolls will bring the body portion of each roll into contact with the side of the binder, and as the flanges on the rolls are forced over the edge of the sole, the binder will be laid firmly and evenly against the 35 outer surface of the upper adjacent to and below the plane of its formed over edge. This binder may be secured in holding position, for example, in the manner disclosed in my method application Serial No. 766,471, 40 or by means such as disclosed in another application Serial No. 259,642, filed October 25, 1918.

By providing rolls having flanges and a formed body portion, the engagement of the 45 rolls with the upper along the edges of the last will smooth or iron out the upper along the edge of the last and by repeating the movement of the rolls in contact with the upper, said edge may be smoothed out and 50 formed down hard and evenly upon the edge of the sole. As the flanges of the rolls are forced between the lower face of the wipers and the underlying upper, they exert a substantial inward wiping action upon the upper 55 the effect of which is to tighten the upper under the wipers. The rolls, in the ways above suggested, always supplement the lasting action of the wipers.

Obviously other binder placing devices 60 than the rolls shown in the drawings may be employed and other changes in the construction and arrangement of parts may be made without departing from the spirit of my invention and I therefore do not limit

myself to any specific construction or arrangement of parts except as expressly required by the terms of the claims. 65

Having thus fully described my invention what I claim is:—

1. The combination with means for forming an upper around and against the end portion of a last, of separate means operable independently of the forming means for engaging the side of a binder and laying the same by lateral pressure thereon around the 70 end portion of the last into contact with the portion of the upper which has been formed over the sole portion of the shoe to hold the upper in position upon the last. 75

2. The combination with means for forming an upper around and against the end portion of a last, of means movable toward and from the end of the last independently of the forming means to engage the side of a binder and lay the same in contact with the upper after the upper has been formed to place by pressure applied to the side of the binder along the portion thereof extending around the end of the last. 80

3. The combination with means for forming an upper around and against the end of a last, of means for holding a binder adjacent to the end of the last, and means for applying pressure along that portion of the binder adapted to engage the formed upper 90 to press the binder laterally into contact with the upper after the upper has been formed. 95

4. The combination with means for forming an upper around and against the end of a last, of means for supporting a binder 100 adjacent to one end of the last, and means for placing said binder in binding engagement with the upstanding edge of the formed over upper while said binder is so supported, by forcing the free ends of said 105 binder toward the sides of the last by pressure applied laterally to the binder along the portion thereof adapted to be engaged with the upper.

5. The combination with means for forming an upper around and against the end of a last, of means adapted to engage a binder intermediate its ends and support the same adjacent to the end of the last with the end portions of the binder projecting 110 freely therefrom, and means operable independently of the forming means for laying the free ends of the binder in engagement with the formed upper. 115

6. The combination with means for forming an upper around the toe portion of a last, of means for holding a binder adjacent to the end of the toe, said means being movable along the binder longitudinally of the last at the two sides thereof simultaneously 120 to progressively force the binder into contact with the upper. 125

7. The combination with means for form-

ing an upper around and against the end portion of a last, of means for holding a binder adjacent to the end of the last, and means movable longitudinally of the binder 5 in contact therewith while the same is held to force the binder laterally into contact with the upper.

8. The combination with end embracing wipers, of means arranged under the wipers 10 to engage one face of a binder and move longitudinally of the binder in contact therewith to force the binder laterally into contact with the upper.

9. The combination with wiper plates for 15 forming an upper upon a last, of separate means for forcing a flexible member into contact with the upper adjacent to said plates, said means being arranged to be moved under the wiper plates along said 20 member longitudinally thereof in contact therewith.

10. The combination with wiper plates for forming an upper around and against the end of a last, of means for applying lateral pressure progressively to a portion of 25 a binder located under the plates after the forming operation is completed and while the upper is held in formed position by said plates, to force said binder into binding 30 engagement with the formed over portion of the upper.

11. The combination with means for forming an upper upon the end portion of a last, of means movable longitudinally 35 along a flexible toe binding member in contact with the outer side thereof to force the portion of the member which is engaged by said means laterally into contact with the upper, and mechanism for moving said 40 means progressively along substantially the entire upper engaging length of said member.

12. The combination with wiper plates for forming an upper around and against the 45 end of a last, of means for holding intermediate its ends a binder adjacent to the end of the last, and means for engaging portions of said binder laterally and forming said portions progressively from the middle portion 50 of the binder longitudinally along the free end portions into contact with the upper.

13. The combination with means for working an upper over the edge of a sole upon 55 a last, of separate means for engaging the side of a binder at a point directly under the overworking means to lay the binder into contact with the overworked portion of the upper.

60 14. The combination with wiper plates for forming the edge portion of an upper over and upon the edge of a sole upon a last, of means movable between the formed over portion of the upper and said plates for 65 laying a binder by lateral pressure in contact

with said portion, after the upper has been formed over the edge of the sole by said plates.

15. The combination with means for working an upper over the edge of a sole upon a last, of a member to engage the formed portion of the upper and the face of a binder and carry the same inwardly over the edge of the sole into engagement with the overworked upper, and means for moving said member over the edge of the sole in contact with said overworked upper to further form the upper and lay the binder in place. 70

16. The combination with wiper plates for forming the edge portion of an upper over 80 the edge of a sole upon a last and against the lip of the sole, of a member to engage the outer side of a binder and move longitudinally thereof, and means for moving said member inwardly over the formed edge portion of the upper and along the binder to lay said binder into the angle of said upper adjacent to the lip.

17. The combination with wiper plates and means for projecting said plates over 90 the edge of a sole upon a last to work an upper over said edge and form it against the lip of the sole, of means for holding a binder adjacent to that face of the plates which is toward the last, a member movable adjacent 95 to said face of the plates in engagement with the side of the binder, and means for forcing said member between the plates and overworked portion of the upper upon the edge of the sole to lay the binder into the 100 angle of the upper adjacent to the lip.

18. The combination with wiper plates, of means for holding a binder adjacent to the contact face of said plates, a member adjacent to said face movable in contact with 105 the side of said binder to force the binder laterally between the plates and edge of the upper which has been formed over thereby, and means for actuating said member.

19. The combination with wiper plates, of means for yieldingly holding a binder against the lower face of said plates, and means movable in contact with said face of the plates to engage and force said binder into engagement with an upper upon a last. 110

20. The combination with means for working an upper around and against the end portion of a last, of means for laying a binder against the formed upper comprising members adapted to be brought into engagement with the upper at the extreme end of the last and thereafter moved to engage the side portions of the upper adjacent to said end, and means for moving said members independently of the means for working the upper. 120

21. The combination with means for forming an upper around and against the end portion of a last, of members for engaging and laying a binder against the formed 130

upper, and carrying means movable in a direction longitudinally of the last for moving said members into engagement with the upper at the extreme end of the last and 5 along the sides of the end portion of the last.

22. The combination with means for forming an upper around and against the end portion of a last, of a pair of members for 10 engaging and laying a binder against the formed upper, and means for supporting said members and engaging the same with the middle portion of the binder adjacent to the end of the last and moving the members along each side of the last to lay the 15 binder progressively in place.

23. The combination with means for forming an upper around and against the end portion of a last, of a pair of members 20 adapted to engage the side surface of a binder and lay the same against the formed upper, a pair of pivoted arms upon which said members are mounted to move toward and from each other, and means for moving said arms bodily in a direction longitudinally of the last.

24. The combination with means for forming an upper around and against the end portion of a last, of a pair of members 30 to engage and lay a binder against the formed upper, means for carrying said members adapted to permit the movement of the members toward and from each other, and means for yieldingly holding the members moved toward each other.

25. The combination with means for forming an upper around and against the end of a last, of a pair of arms pivotally supported at one end and free to swing to 40 ward and from each other at their opposite ends, members carried by the free ends of said arms for engaging and laying a binder against the formed upper, and means for moving the arms and last relatively to bring the members into contact with the end of 45 the shoe and move the same along the sides thereof.

26. The combination with means for forming an upper around and against the 50 end of a last, of a supporting member reciprocable toward and from the end of the last, a pair of arms pivotally attached at one end to said member, means for yieldingly turning the arms toward each other, members 55 on the free ends of said arms to engage a binder and force the same into engagement with the formed upper, and means for reciprocating the supporting member.

27. The combination with wiper plates 60 for forming an upper over and against the end portion of a last, of a roller and means for moving the roller toward and along the last to engage a binder and lay the same in contact with the formed over edge of the 65 upper.

28. The combination with wiper plates for forming an upper against and over the end portion of a last, of means for supporting a binder adjacent to the end of a last, a roller to engage the binder, and means for 70 moving said roller along the last adapted to yieldingly hold the roller in contact with the upper and binder.

29. The combination with means for forming an upper against the end portion 75 of a last, of a tool having a portion adapted to project over the edge of the last, and means for moving said tool along the last in shaping contact with the upper.

30. The combination with means for 80 forming an upper over and against the end portion of a last, of means for supporting a binder adjacent to the end of the last, a roller to engage the binder and formed to conform to the shape of the bottom surface 85 of the last along the edge thereof to form the upper down thereon and lay the binder at an even distance from the edge of the last, and means for moving the roller along said edge.

31. The combination with wiper plates for working an upper over the edge of a sole upon a last, of means for supporting a binder adjacent to the end of said last, a roller to engage the binder and shaped to 95 form down the overworked edge of the upper and project beneath the plates, and means for forcing said roller between said plates and formed edge of the upper along said edge of the last.

32. The combination with means for working an upper over the edge of a sole upon a last, of a tool having a flange adapted to project over the overworked edge of the upper and to engage and carry a binder 105 over said edge into engagement with the upper, and means for moving the tool along the last.

33. The combination with wiper plates and means for projecting said plates over 110 the edge of a sole upon a last to form the edge of an upper upon the last down upon said edge of the sole, of a tool having a flange to engage a binder, and means for moving the tool to force the flange between 115 said overworked edge of the upper and said plates.

34. The combination with wiper plates and means for projecting said plates over the edge of a sole upon a last to form the edge of an upper upon the last down upon 120 said edge of the sole, of a roller having a flange to engage a binder and a body portion formed to conform to the upper along said overworked edge portion thereof and form the same to the last and the edge face of the sole, and means for moving said roller along the last.

35. The combination with means for forming an upper against the end portion 130

of a last, of tools adapted to engage a binder and lay the same against said formed portion of the upper, and means for simultaneously moving said tools into engagement with the upper at the end of the last along the sides of the end portion of the last.

36. The combination with wiper plates for engaging and forming an upper against the end portion of a last, a carrying member for said plates, and means for moving said carrying member; of a member to engage a binder and lay the same against the formed upper, and means for supporting said member carried by and movable with the carrying member for the wiper plates.

37. The combination with means for working an upper into engagement with a last, of a member for engaging and laying a binder into engagement with the upper, means for holding a binder in the path of said member, and means for moving said member into engagement with the binder to force the same into engagement with the upper.

38. The combination with wiper plates for working an upper into engagement with a last, of a member movable adjacent to the face of said plates and adapted to engage one side of a binder for forcing the binder by lateral pressure beneath said plates into engagement with the upper upon the last, and a spring finger adjacent to the said face of the plates to hold the binder in the path of said member.

39. The combination with wiper plates for forming an upper around and over the end of a last, and a movable carrier member for the wiper plates, of a support attached to and movable with the carrier member, means carried by the carrier member for supporting a binder adjacent to the wiper plates, and a member on said support for engaging the binder, and means for moving said member to force the binder between the plates and formed over edge of the upper.

40. The combination with wiper plates, and a carrier member for said plates, of means positioned by said carrier and movable lengthwise of the shoe edge for forcing a binder between said plates and a portion of the upper overwiped upon the shoe bottom by the plates, and means carried by the carrier member for supporting a binder in position to be engaged by said means for laying it against the upper.

41. The combination with wiper plates for forming an upper around and against the end of a last, of a tool for laying a binder against the formed upper, means for carrying and moving the tool, and means movable with said carrying means for supporting a binder in position to be engaged by the tool.

42. The combination with means for forming an upper around and against the end of a last, of a pivoted arm extending in a direction longitudinally of the last with its free end adjacent to the end of said last, an upwardly extending post on said arm, a roll pivotally supported upon the upper end of the post in position to engage a binder and force the same into contact with the formed upper around the end of the last, and a spring finger carried by the post to support a binder in position to be engaged by the roll.

43. The combination with a last support and means for forming an upper upon the last around and against the end thereof, of means for supporting a binder adjacent to the end of said last, a roll for laying the binder in engagement with the formed upper, a pivoted arm for carrying the roll, a reciprocable member to which the arm is attached, and a guide for the reciprocable member positioned with its longitudinal axis in the vertical plane of the center line of the last and with one end thereof adjacent to the end of the last.

44. The combination with wiper plates and a rocking-head for carrying said plates, of a tool supported adjacent to one face of the wiper plates, a reciprocable carrying member for the tool, a guide for the reciprocable member attached to and movable with the head, and means for moving the reciprocable member independently of the movement of the head and wiper plates.

45. The combination with means for forming an upper around and against the end of a last, of a tool for engaging a binder to lay the same against the formed upper, a post for carrying the tool, reciprocable means upon which the post is mounted, a finger pivotally supported upon the post, and means for yieldingly holding the finger and limiting the turning movement thereof.

46. The combination with wiper plates for forming an upper around and against the end of a last, of a pair of tools adjacent to the end of the last, a pair of arms pivotally supported at one end and carrying the tools at their free ends, means for yieldingly holding the arms turned to bring the tools toward each other and adapted to yield to allow the arms to spread apart as the tools are brought into engagement with the side portions of the end of the last, a reciprocable member to which the arms are pivotally attached, means for supporting the arms intermediate their ends, and means for actuating the reciprocable member toward and from the end of the last.

47. The combination with wiper plates for forming an upper around and against the end of a last, and a pivotally supported head for carrying the plates, of a guide carried by the head and movable therewith, a reciprocable member mounted upon the guide to

reciprocate toward and from the end of the last, arms pivotally attached at one end to the reciprocable member, posts on the free ends of the arms, tools mounted upon the 5 upper ends of the posts to engage the binder and lay the same against the formed upper around the end of the last, an arm carried by each post and projecting laterally therefrom adjacent to the wiper plates to support 10 a binder in position to be engaged by the tools, and means for reciprocating the reciprocable member.

48. The combination with wiper plates for forming an upper around and against the 15 end of a last and a pivoted head for carrying said wiper plates, of a guide carried by the head to move therewith, a reciprocable member on the guide adapted to be reciprocated toward and from the end of a last, 20 pivoted arms attached at one end to the reciprocable member and supported intermediate their ends by the guide, posts on the free ends of said arms, tools on the upper ends of the posts to engage a binder and lay 25 the same against the formed upper, a finger pivotally supported at one end by each post to extend laterally therefrom adjacent to the tool and adjacent to one side of the wiper plates to hold a binder in position to 30 be engaged by the tools, means for yieldingly holding each finger against turning, a spring connecting the arms to resist the swinging of the same from each other, and means for moving the reciprocable member to actuate 35 the arms longitudinally toward the end of the last.

49. The combination with means for forming an upper around and against the end of a last, of a tool for laying a binder against the formed upper, a post upon which the 40 tool is pivotally supported, a pair of fingers carried by the post and pivotally supported at one end adjacent to the tool, means for resisting the turning of the fingers, and carrying means for the post reciprocable toward and from the end of the last.

50. The combination with wiper plates for forming an upper around and against the end of a last, of a tool having a flange 50 at one end for engaging a binder to lay the same against the formed over edge of the upper upon the last, said tool also having a formed portion adapted to engage the upper adjacent to the formed over edge 55 thereof and form the same down upon the last simultaneously with the laying of the binder in place, and means for supporting and moving the tool along the last.

51. The combination with means for 60 forming an upper around the toe portion of a last, of means for engaging a portion of a binder which is to be applied to the shoe and by pressure laying said portion of the binder around the end of the toe and along the sides 65 of the forepart of the shoe into contact with

the formed portion of the upper to hold the upper in position upon the last.

52. The combination with means for forming an upper around the toe portion of a last, of separate means for engaging substantially the entire side of a binder and pressing different upper engaging portions of the binder successively against the upper after the completion of the lasting into position to hold the lasted upper. 75

53. The combination with means for engaging a toe binder at opposite sides of the toe of a shoe, of operating mechanism for causing said engaging means to move along the binder to lay the binder into binding 80 position progressively along said opposite sides of the toe simultaneously by engagement successively with different portions of the binder extending substantially from the toe end of the shoe rearwardly along the 85 sides.

54. The combination with means for forming an upper around the toe portion of a last, of separate means arranged for operation after the completion of the operation 90 of said forming means to engage a binder and lay the binder around the toe along the sides of the forepart into position to hold the upper.

55. The combination with means for forming an upper around the toe portion of a last, of means movable toward and from the toe end of the last independently of the forming means to engage a binder and lay the binder in contact with the formed upper by 100 pressure applied to the outer side of the binder. 95

56. The combination with means for forming an upper around the toe of a last, of means for holding a binder adjacent to the toe of the last, and means operable independently of the forming means for bending the binder around the toe and pressing the binder laterally into contact with the upper. 105

57. The combination with means for forming an upper around the toe of a last, of means for supporting a binder adjacent to the toe of the last, said last-named means being adapted for operation to place the 115 binder in binding engagement with the upper by transferring points of application of the binder progressively along the two sides of the shoe from the end of the toe backwardly. 110

58. The combination with toe embracing wipers adapted for shaping an upper to the toe end of a last, of means adapted to engage a toe binder intermediate its ends and support the binder adjacent to the end of the toe with the end portions of the binder projecting freely from the support, said means being arranged for operation to apply the binder in holding engagement with the upper around the toe. 125

59. The combination with means for lasting a toe, of means for supporting a binder adjacent to the end of the toe, and additional means movable longitudinally of the binder 5 in contact therewith at the two sides of the toe simultaneously to force the binder laterally into binding relation to the lasted upper. 70
60. The combination with toe embracing 10 wiper plates, of a member located below and adjacent to said plates and normally retracted from the acting edge of the plates at the end of the toe, said member being movable into contact with the side of a toe 15 binder to force the binder laterally between the plates and the edge of the upper which has been laid over the last by said plates, and means for operating said member. 75
61. The combination with means for 20 manipulating an upper about the toe portion of a last, of upper forming members adapted to be brought into engagement with the upper at the extreme end of the toe and moved over a marginal portion of the shoe 25 bottom, and thereafter moved into engagement with and over the side portions of the upper adjacent to said end, and means for moving said members independently of the first-mentioned means. 80
62. The combination with means for 30 manipulating an upper about the toe portion of a last, of a pair of rolls constructed and arranged to lay the upper over the marginal portion of a sole, and means for 35 supporting said rolls and engaging them with the work at the toe end of the shoe and moving them along the opposite sides of the toe backwardly to lay the upper progressively into place upon the margin of 40 the sole. 85
63. The combination with means for 45 manipulating an upper about the toe portion of a last, of a pair of upper overlaying devices, and means for supporting said devices and engaging them with the work at the toe end of the shoe and moving them along the opposite sides of the toe backwardly to lay the upper progressively into place upon the margin of the shoe bottom. 90
64. The combination with means for 50 manipulating an upper about the toe portion of a last, of a pair of upper forming tools arranged with relation to said means to engage the side faces of the shoe at the end of 55 the toe, and operating means for moving said devices backwardly to form the upper to the side faces of the toe progressively from the end of the toe backwardly along 60 opposite sides of the toe of the last. 100
65. The combination with means for 65 forming an upper around the end of a last, of a pair of arms pivotally supported at one end and free to swing toward and from each other at their opposite ends, members carried by the free ends of said arms for en- 105
- gaging against the formed upper, means for moving the arms and last relatively to bring the members into contact with the end of the shoe and move the same along the sides thereof, and means for holding said members yieldingly toward each other and allowing them to adapt themselves to the width and shape of the last. 110
66. The combination with means for manipulating an upper into lasted relation to 75 the side faces of the toe portion of a last, of a tool arranged for operation after said upper has been worked into lasted position around the toe, and means for moving the tool progressively along the edge of the toe 80 in contact with the upper for forming the upper to the last at and adjacent to the edge of a shoe bottom. 85
67. The combination with means for manipulating an upper into lasted relation to 90 the side faces of the toe portion of a last, of a tool shaped to conform substantially to the contour of the shoe at the edge of the shoe bottom and on the lateral periphery of the shoe adjacent to said edge, and means for moving the tool along said edge to shape 95 the upper to the last. 100
68. The combination with means for working an upper over the margin of the toe portion of a sole upon a last at a single 95 operation, of a tool shaped to form down the overworked margin of the upper, means for operating the overworking means, and means for moving said tool along said overworked margin lengthwise of the last edge. 100
69. The combination with means for manipulating an upper into conformity with the side faces of the entire toe portion of a last, of a tool shaped to form the margin of the upper inwardly and downwardly upon 105 the margin of a sole on the last bottom, and means for moving said tool along said margin lengthwise of the edge of the shoe bottom after the operation of the first-named means. 110
70. The combination with means for manipulating an upper into substantial conformity with the side faces of the toe portion of a last, of a tool having a flange and a body portion shaped and arranged respectively for forcing the upper inwardly over the edge of a sole on the last and for shaping the upper into conformity with the contour of the last and the edge face of the sole adjacent to the shoe bottom, and means 115 for effecting relative movement of the tool and the last for the purpose described. 120
71. The combination with lasting means comprising toe embracing means, means for determining the vertical position of the fore-part of a last, and mechanism for relatively operating said means for manipulating an upper into substantial conformity with the contour of the side faces of the toe portion of the last, of a tool so constructed and ar- 125

- ranged and the vertical position of which is so related to said lasting means that the tool is adapted to engage the shoe at and adjacent to the edge of the shoe bottom, and 5 means for moving the tool along the toe of the shoe for forming the upper to the last and sole.
72. The combination with wiper plates for working an upper into engagement with the 10 forepart of a last, of a tool movable lengthwise of the last edge from the end of the toe rearwardly in a plane adjacent to the lower face of said plates for forcing a binder into engagement with the upper upon the last.
- 15 73. The combination with toe embracing plates, a movable carrier for the plates, and means for determining the relative vertical planes of the plates and the shoe bottom, of a toe binder support attached to and vertically positioned by the plate carrier; and 20 means for laying the binder into binding relation to the upper around the toe of the last.
74. The combination with wiper plates and a carrier for said plates, of means positioned by said carrier and including a member bodily movable lengthwise of the shoe edge for forcing a binder between said plates and a portion of the upper overwiped upon the shoe bottom by the plates.
- 25 75. The combination with means for manipulating an upper into substantial conformity with the contour of the side faces of the toe of a last, of a device movable lengthwise of the last edge from the toe end 30 rearwardly for progressively clamping a binder into binding relation to the upper, and means for carrying and moving the binder clamping device.
76. The combination with means for forming an upper around and against the end of 35 a last, of a pivoted arm extending in a direction lengthwise of the last with its free end adjacent to the end of the last, an upwardly extending post on said arm, a tool supported 40 upon the upper end of the post in position to engage the work substantially at the edge of the shoe bottom, and means for moving said arm to cause the tool to operate progressively along the edge of the shoe bottom.
- 45 77. The combination with means for forming an upper around and against the end of a last, of a tool for laying a binder in engagement with the formed upper, a pivoted arm for carrying the tool, and means 50 for reciprocating said arm to cause the tool to apply the binder progressively lengthwise of the edge of the last.
78. The combination with means for holding a binder across the toe end of a shoe, 55 of means for applying pressure successively to different portions of said binder extending substantially from the toe end of the shoe rearwardly to lay said binder into holding relation to the upper along the two sides of the toe.
79. The combination with means for sustaining a binder across the toe end of a shoe, of means for operating the sustaining means to apply pressure successively to different portions of the binder for laying 70 the binder progressively in holding relation to the upper along the two sides of the toe simultaneously.
80. The combination with binder holding and placing means constructed and arranged to sustain a binder with an intermediate portion thereof adjacent to the end of the toe of a shoe, of operating mechanism for forcing the intermediate portion of the binder into contact with the end of the toe 75 and then applying pressure successively to different portions of the binder extending from the end of the toe rearwardly to lay it progressively toward its ends into binding relation to the upper along the sides of the toe.
81. The combination with means for working an upper into position against the toe of a last, of means for sustaining a binder adjacent to the end of the toe and 80 forcing the binder into contact with the lasted portion of the upper progressively along each side of the last by pressure against the outer side of the binder.
82. The combination with means for working an upper into position over the toe end of a sole on a last, of means for sustaining a binder adjacent to the end of the toe, and operating mechanism to force the binder into upper binding position progressively along the two sides of the toe from the end rearwardly and simultaneously to form the upper down upon the margin of the sole adjacent to the binder.
83. The combination with toe embracing wipers for working an upper over a last and into lasted position against the lip of a sole, of means for rolling a binder into toe binding position under the wipers.
84. The combination with means for working an upper into lasted relation to the side faces of the toe of a last, of means for rolling a binder into binding relation to the upper around the toe.
85. The combination with means for working an upper into lasted relation to the side faces of the toe of a last, of means for applying a binder in binding relation to the upper exteriorly of the periphery of the last bottom around the toe.
86. The combination with suitable operating mechanism, of devices actuated thereby for laying a binder into contact with a lasted end portion of a shoe by engaging the binder initially at the end of the last and then progressively along the sides of the last from said initial location to force the binder into engagement with the upper along each side of the end portion of the last.

87. The combination with suitable operating mechanism, of devices actuated thereby for laying a binder into contact with a lasted end portion of a shoe by engaging the binder initially at the end of the last and then progressively along the sides of the last from said initial location to force the binder into engagement with the upper along each side of the end portion of the last from the end thereof rearwardly, said mechanism and devices being constructed to hold the binder in the clamping engagement with the upper for its ends to be anchored.
88. The combination with means for manipulating an upper into substantial conformity with the contour of a last around the toe below the shoe bottom, of means constructed and arranged for applying a flexible binder around the toe below the bottom of the shoe.
89. The combination with means for manipulating an upper into substantial conformity with the contour of a last around the toe below the shoe bottom, of means constructed and arranged for applying a flexible binder progressively from the end of the toe backwardly and simultaneously along opposite sides of the toe exteriorly of the last bottom.
90. The combination with means for manipulating an upper into substantial conformity with the contour of a last around the toe below the shoe bottom, of suitable operating mechanism, and means connected therewith and constructed and arranged for applying a strip or ribbon of binding material tightly around the toe below the bottom of the shoe in position to leave the margin of the upper free above the sole bottom for manipulation in a subsequent upper and sole connecting operation.
91. In a machine for lasting shoes, the combination with means for working an upper into lasted position at the end and the opposite sides of the end portion of a shoe substantially simultaneously, of means

for supporting a lasting binder in position to be applied to the shoe, and additional means for engaging the binder as thus supported and forcing it into holding relation to the upper by pressure directed laterally against the shoe engaging portion of the binder.

92. In a machine for lasting shoes, the combination with end embracing wipers and means for operating them to wipe the upper of a shoe over the margin of the sole, of means for positioning a lasting binder substantially contiguous to the overwiping faces of said wipers, and means movable along said faces in engagement with the binder to force it into holding relation to the overwiped upper at the opposite sides of the end portion of the shoe.

93. In a machine for lasting shoes, the combination with shoe positioning means, of end embracing wipers, means for operating said wipers to wipe the upper of the shoe over the margin of the sole, means for supporting a lasting binder under said wipers, and means for engaging said binder and forcing it in between the wipers and the overwiped margin of the upper by pressure directed laterally against the shoe engaging portion of the binder.

94. In a machine for dasting shoes, the combination with shoe positioning means, of end embracing wipers, a support for said wipers movable lengthwise of the shoe, means movable with said support and arranged to position a lasting binder substantially contiguous to the overwiping faces of the wipers, and means movable relatively to said support and wipers to force the binder into holding relation to the upper at the opposite sides of the end portion of the shoe.

In testimony whereof I affix my signature in presence of two witnesses.

CHARLES F. PYM.
